Primary Examiner — Deanna L Pratt(57) **CLAIM**

The ornamental design for a separable and rotatable input device, as shown and described.

DESCRIPTION

FIG. 1 is a front perspective view of a separable and rotatable input device showing my new design;

FIG. 2 is a top side view thereof;

FIG. 3 is a top side view in a separated position thereof;

FIG. 4 is a top side view in a rotated position thereof;

FIG. 5 is a rear view thereof;

FIG. 6 is a front view thereof;

FIG. 7 is a right side view thereof;

FIG. 8 is a left side view thereof;

FIG. 9 is a front perspective view showing an attaching and rotating mechanism thereof;

FIG. 10 is a rear perspective view showing an attaching and rotating mechanism thereof; and,

FIG. 11 is a bottom side view.

The broken lines in the drawings illustrate the boundaries of the claimed design. Both the boundary lines and the areas therewithin form no part of the claimed design.
